UNITED STATES PATENT OFFICE.

FRANK DE SILVA, OF MELROSE, MASSACHUSETTS.

DIRECTORY-BOARD.

1,121,809.

Specification of Letters Patent. Patented Dec. 22, 1914.

Application filed January 22, 1914. Serial No. 813,813.

To all whom it may concern:

Be it known that I, FRANK DE SILVA, a citizen of the United States of America, and a resident of Melrose, in the county of Middlesex and State of Massachusetts, have invented certain new and useful Improvements in Directory-Boards, of which the following is a specification.

This invention relates to directory or bulletin boards, such, for example, as those used at the entrance of large buildings giving the names and locations of the tenants, and more particularly to such boards on which the reading matter is made up of a series of unitary blocks bearing a letter of the alphabet or other character.

The object of the invention is to provide a directory board which is strong and rigid in structure, free from loose parts and easy to operate when the matter displayed is to be changed.

A further object is to provide a board on which the signs may be changed without the aid of a skilled operator, or the necessity of any particular training in the operation of the board.

These objects and such others as may hereinafter appear will best be understood from the following description and accompanying drawings of the preferred embodiment of the invention.

Of the drawings: Figure 1 is a front elevation of a directory board adapted for use in an office building. Fig. 2 is a section on the line 2—2 on Fig. 1. Fig. 3 is an end view of a portion of the board, certain parts being shown in section. Fig. 4 is a detail view, on an enlarged scale, of one of the channel strips for retaining a line of character bearing blocks. Fig. 5 is an end view of the same. Figs. 6 and 7 are detail views of the front and back members of a character block. Fig. 8 is a vertical section through a character block, the front and back members being separated. Fig. 9 is a front view of a character block, and Fig. 10 is a vertical section through the block shown in Fig. 9.

Similar characters designate like parts throughout the several figures of the drawings.

In the drawings, the directory board is illustrated as comprising a back board 10, which carries the reading matter, surrounded by a frame 11 to which is hinged a door 12. The door is divided vertically by a bar 13 and provided with two windows 14, by

which the board is adapted to display two vertical columns of names. Each name or line of reading matter is carried in a channel plate 15, shown in detail in Figs. 4 and 5. The channel plates are preferably made from pieces of sheet metal of sufficient length to accommodate a line of the desired length and having the longitudinal edges 16 turned inwardly toward the front thereof so as to form a shallow dovetailed groove on the front side of the plate to receive the character blocks. The channel plates are removably mounted on the back board 10 by inserting flat lugs or extensions 17 extending from each end of the plate into notches 18 formed in vertical strips 19 which project from the back board 10. The notches 18 in each pair of strips 19 are alined. The lugs 17 are located near the upper edge of the plate 15 and are of such width as to fit snugly into the bottom of the notches 18. The notches 18 are dovetail in shape having their upper and lower edges inclined inwardly toward the front edge of the strip so that the opening at the edges is of less width than the width of the flat extensions 17 of the plates 15, thereby preventing the removal of said plates until they are tipped at an angle to said back board 10. The rear edge of the notches 18 are somewhat in front of the front face of the back board 10 and between the plates 15 and the front face of said board and secured to the latter are a plurality of magnets 20 inclined at angle to the edges of said back board with their ends in echelon. These magnets 20 are disposed in vertical rows so that when the plates 15 are positioned, the opposite ends of each plate will contact with the front faces of a plurality of said magnets 20 and not only act as a keeper therefor but will, through the magnetic contact with said plates 15 prevent the latter from rattling or becoming displaced from the vertical strips until such time as they may be forcibly separated therefrom and moved into an inclined position for the purpose of removal.

The character blocks 21 are formed of two cup-shaped members 22 and 23, the latter being smaller than the former. The edges of the member 22 are turned inwardly toward the rear, and inclose the flanges of the member 23, as shown in Fig. 10. The front face of the member 22 is provided with a character 24, such as a letter or figure. When the two members 22—23 have been

joined together in the manner described, the edges of said block are straight with the faces of said edges inclined inwardly toward the rear of the block. When the block 5 21 is inserted between the inturned inclined flanges of the plate 15 with the outer face of the member 22 facing outwardly as indicated in dotted lines in Fig. 5 it is self-evident that the frictional contact between the 10 upper and lower edges of the block 21 and the flanges of the plate 15 will be reduced to a minimum and the movement of the blocks longitudinally of the plate will be greatly facilitated.

15 It is obvious that with a directory board thus constructed the superintendent of any building where such a board is installed may readily make any desired changes therein without the necessity of having new name 20 plates made as is now the case. It is also evident that each name plate may be quickly and readily removed without in any manner disturbing the remaining name plates. By the use of the magnets disposed in the rear 25 of the plates the rattling of the plates will be effectually prevented when the building is shaken by passing traffic.

It is believed that the operation and many 30 advantages of the invention will be fully understood from the foregoing description.

Having thus described my invention, I claim:

1. In a device of the class described, the combination of a back board; vertical strips 35 at the ends thereof provided with a plurality of notches in the front edges thereof, the notches in one strip being alined with the corresponding notches in the other strip; a character-block-carrying plate having at its ends 40 adjacent to the upper edge thereof extensions adapted to be positioned in two alined notches; and magnets on the front face of said back board coacting with opposite ends of said plates to prevent movement thereof.

2. In a device of the class described, the 45 combination of a back board; vertical strips at the ends thereof provided with a plurality of dovetail notches in the front edges thereof, the notches in one strip being alined with the corresponding notches in the other strip; 50 a character-block-carrying plate having at its ends adjacent its upper edge extensions adapted to be positioned in two alined notches; and magnets positioned on the front face of said back board with their 55 ends in echelon and coacting with said strips to prevent movement thereof.

3. In a device of the class described, the combination of a backboard; vertical strips 60 at the ends thereof provided with a plurality of dovetail notches terminating in narrow openings at the front edges thereof midway of said notches, the notches in one strip being alined with the corresponding notches in the other strip; and a plate having flat ex- 65 tensions at opposite ends near the upper edge adapted to be positioned in said alined notches.

4. In a device of the class described, the combination of a backboard; vertical strips 70 at the ends thereof provided with a plurality of dovetail notches terminating in narrow openings at the front edges thereof midway of said notches, the notches in one strip being alined with the corresponding notches in the other strip; a plate having flat extensions 75 at opposite ends near the upper edge adapted to be positioned in said alined notches; and means behind the opposite ends of said plate to prevent movement thereof about the 80 axis of said extensions.

Signed by me at 4 Post Office Sq., Boston, Mass., this 19th day of January, 1914.

FRANK DE SILVA.
